RAIL DETECTOR PICKUP AND COIL

Chester W. McKee and Richard W. McKee, Chicago, Ill., assignors, by mesne assignments, to Teleweld, Inc., a corporation of Idaho

Application November 15, 1951, Serial No. 256,502

1 Claim. (Cl. 324—37)

This invention relates to a rail detector pickup and coil. It has been developed primarily for use in the Tele-detector fissure detector car and to replace in part the pickup coil and assembly disclosed in copending application Serial No. 72,382, filed January 24, 1949, which has issued into Patent No. 2,639,316, dated May 19, 1953.

The pickup coil disclosed in that application consists of a cylindrical spool having an annular channel at right angles to its axis one-sixteenth of an inch from the lower end and a similar annular channel upwardly one-half inch. The spool is one-half inch in diameter and one inch high, and is mounted in a multiple pickup coil assembly by positioning it in a cylindrical cavity in a non-conductive block with its axis at right angles to the ball surface. The two channels contain respectively a large number of windings of fine wire, the turns in the upper channel being reversed in direction to the turns in the lower windings and both being series connected to each other with their respective other leads connected to ground and the input of an amplifier. The lower coil is close to the rail and is principally responsible for generating potential signals significant of physical abnormalities in the rail structure. The upper coil serves to produce an offsetting potential signal whenever the pickup coil cuts lines of force due to vertical movements of the coil with respect to the rail.

The arrangement shown in this copending application was practical for a car having light magnets and high gain amplifiers. More recently, applicants have built a car with very heavy magnets which establish a very strong field. The old pickup coils had no difficulty in picking up five to ten percent fissures, but the large fissures were missed, indicating that the upper coil was canceling the lower coil when a great change in the flux field, as by a large fissure, occurred.

One object of this invention is to eliminate this difficulty by moving the upper or bucking coil to a point behind the lower coil in the same horizontal plane. By experiment it was determined that this was superior to moving the upper coil further above the lower coil. The disadvantage of doubling the number of potential signals in traversing a selected flux field was outweighed by the advantage of positioning the two coils at the same distance above the rail, due to the lack of sensitivity of the pen unit.

A second object of this invention is to keep the over-all length of the two coils lying side by side as short as possible, while retaining the feature of non-magnetic cores in the coils. In accomplishing this, applicant adopted an elongated (in cross section) core positioned transversely of the rail which has the joint effect of reducing the amount of wire that is merely threading a trailing sustained field where the flux is moving in vertical planes parallel to the length of the rail and of increasing the amount of wire that is moving squarely at right angles to such lines of flux.

Another object of this invention is to eliminate the skipped space between the side-by-side but spaced pickup

2

coils shown in the copending application. Channel checking of a rail has proved successful. Not only does it enable an operator to more exactly locate the transverse position of a fissure before hand checking, but a skilled operator by comparing the action of the pens writing the gauge or field channels with the next adjacent pen, can spot shells and flows on the rail ball edges which he cannot clearly see from his seat. A feature of the present invention is the retention of the pickup block, with, however, the spool recesses substantially touching each other and the spools themselves substantially touching each other.

Another object of this invention is to more carefully search the rail ball on the gauge side of center. The most common place for fissures to start is beneath that point of a rail ball which receives the heaviest wheeling, and that place is slightly to the gauge side of center. A feature of this invention is the provision of a channel with coils that slightly overlaps each adjacent channel so that the smallest internal gap in the continuity of the rail lying at the edges of this important channel will not be missed.

These and such other objects as may hereinafter appear are attained in the embodiment of the invention shown in the accompanying drawings, wherein:

25 Fig. 1 is a side elevation of a pickup carriage illustrating the position of the pickup;

Fig. 2 is a perspective illustration of the pickup block showing in exploded fashion two different types of spool coils ready for mounting in said block;

30 Fig. 3 is a view taken on the line 3—3 of Fig. 2;

Fig. 4 is a view taken on the line 4—4 of Fig. 2;

Fig. 5 is a view taken on the line 5—5 of Fig. 2;

35 Fig. 6 is a plan view of the pickup over a rail taken with a schematic wiring diagram illustrating how the coils are connected to a pen over a tape; and,

Figs. 7 and 8 are schematic illustrations of a side elevation and plan view of the lines of flux of applicants' trailing sustained field.

40 Continuing to refer to the drawings, applicants' pickup utilizes nine pickup coils or spools varying in diameter from one-half to three-quarters of an inch. The teaching of copending application Serial No. 72,382, filed January 24, 1949, as to how to mount such small coils in exact relationship to each other in a block is followed here. 45 The numeral 10, referring to Fig. 1, identifies a block of non-magnetic and electrically non-conductive material, which is suspended by any suitable means from a plate 12 which in turn is suspended from a frame 14 riding on four pairs of wheels 16, 18, 20 and 22, these numbers designating the near wheels only. The frame 12 is hung by hangers 24 and 26 from a fissure detector car, not shown.

Examining now the pickup block, and referring to Fig. 2, this block has drilled through it four pairs of holes, 28 and 60, 30 and 62, 32 and 64, and 34 and 66, and a single hole 36. Referring to Fig. 6, where we are looking downwardly on the block, the position of the block over a 131 pound rail 38 is illustrated. The width of the head of that rail is substantially covered by the pairs of openings, 28, 30, 32 and 34. The diameter of the openings of the holes 28, 30 and 32 is slightly less than the diameter of the holes 34, and the holes 34 are positioned rearwardly of the transverse alignment of the holes 28, 30 and 32 in order that the longitudinal path of these holes along the rail will overlap the path of the inside edges of the holes 30 and 32. The bottoms of the holes are closed by a plastic plate 46, see Fig. 1, which is screwed to the block 10.

Returning now to Fig. 2, one of applicants' spool-type 70 coils in perspective is designated by the numeral 42. This coil, referring also to Figs. 3, 4 and 5, consists of a cylinder or spool of non-conductive material 44 which has had

cut in it a deep parallel slot 46, leaving a cap or spacer piece 48 held to the main spool by a land 50 which is rectangular in cross section, see Fig. 5. Around this land is wound several thousand turns of fine wire 52, and the coil has the cross sectional configuration illustrated in Fig. 5. By placing this spool in a hole such as 32, see Fig. 6, with the land 50 at right angles to the length of the rail 38, there is provided a large quantity of straight wire between the arrows 54 and 56, on each side of the land or core 50, which is cutting the lines of flux in applicants' trailing sustained field at right angles. Applicants' trailing sustained field may be regarded as one in which the flux is moving through a magnetic core, see Figs. 7 and 8, through the portion of the rail just traversed by the core and thence emerging from the rail at varying angles depending upon the distance from the core into the air and back to the magnet. Viewed from above as in Fig. 8, it may be said that the flux is moving in vertical planes parallel to the length of the rail. This is not wholly true but generally true. It is evident, therefore, that in order to most squarely cut this flux, wires running transversely of the rail, as those between the arrows 54 and 56 of Fig. 6, will be most effective. For the same reason wire which is running parallel to the length of the rail will be merely threading flux and not likely to indicate changes in flux direction or flux density. The pickup coil 42 here disclosed minimizes the amount of wire that will be threading flux in a trailing sustained field and increases the amount of wire that will be cutting such flux at right angles as compared with a coil having a circular vertical core with the wires circularly wound.

The leads from a coil of the type 42 are carried up suitably positioned channels 57 and 58. Applicants wind right-handed coils and left-handed coils. Each pair of openings such as 28, see Fig. 2, contains one right-hand and one left-hand wound coil, and the lead holes 60, 62, 64 and 66 will always have similarly wound coils, that is, all right-hand wound or all left-hand wound. As stated, each pair of coils is connected to each other in series so that they will generate opposing signals due to vertical movements of the block 10 and the lead of one coil is grounded as at 68 in Fig. 6 while the lead from the other coil is carried to a separate amplifier 70 which by conductors 72 and 74 may actuate a pen unit such as 76.

Spools 42 are dropped into position in the block 10, the fit being snug and the wire connections may be made on the top of the block. Spools are easily replaced. For rail having a substantially narrower head, the applicants may provide a correspondingly narrower block with a similar arrangement of slightly smaller coils.

In moving this pickup block along the rail, applicants obtain excellent channel testing. The larger spools seated in the openings 34 and 66 were designed so that the edge of the spools at 78 and 80 would surely overlap the edges

of the adjacent spools 82 and 84 because the side 86 of the rail 38 is the gauge side and most fissures start a little to the left of the median line 88 of the rail ball.

From the visual signal standpoint, a 39-foot rail being written on two inches of tape 90, there will be no appreciable transverse difference in the markings on the tape due to the fact that the signals received from the coil in the recess 34 will be slightly later than those received from the other three pairs of coils.

The single hole 36, Fig. 2, receives a coil spool 92 which is of the same type as that described in copending application Serial No. 72,382. Here a lower winding 94 is connected in series opposition to an upper winding 96, and one lead is grounded at 98, Fig. 6, and the other lead goes to the amplifier 100 and thence to the pen unit 102, and the controls of this individual detector line are set so that when the coil 92 passes over a rail joint, a marking on the tape will be made comparable to that made by the other four pen units which respond to much more sensitive amplification. This means that this detection channel will not record even a large fissure. It records only breaks in the rail.

All of the coils have non-magnetic cores and, lengthwise of the rail, are mounted in touching engagement in order to keep the over-all length of each pair of coils as short as possible. A fissure flux field in all longitudinal magnetic testing (as contrasted to the current system) has an appreciable length of approximately an inch, irrespective of the size of the fissure, but short of an actual break in the rail.

Having thus described our invention, what is claimed is:

A fissure detector assembly comprising a frame having a leading edge, a plurality of pairs of substantially touching coils with vertical axes and non-magnetic cores mounted on said frame, the pairs of coils being in alignment parallel with the leading edge excepting for one pair disposed in touching engagement with adjacent pairs but therebehind, the coils of each pair being wound in series opposition and connected to a separate amplifier, and conductors leading the output of each amplifier to a separate pen unit forming part of a battery of pen units positioned over a single moving tape.
